[57] CLAIM

The ornamental design for an automobile tire, as shown and
described.

DESCRIPTION

FIG. 1 is a front perspective view of an automobile tire
showing my new design, it being understood that the tread
design is repeated uniformly throughout the circumference
of the tire;

FIG. 2 is a front elevational view thereof;

FIG. 3 is a top plan view thereof;

FIG. 4 is a left side elevational view thereof;

FIG. 5 is a right side elevational view thereof; and,

FIG. 6 is a enlarged fragmentary front elevational view
thereof.
